UNITED STATES PATENT OFFICE.

FREDERICK M. TURCK, OF NEW YORK, N. Y., ASSIGNOR OF ONE-HALF
TO CHARLES W. TRACY, OF NEW YORK, N. Y.

ROTARY PRINTING-PRESS.

No. 830,751.

Specification of Letters Patent.

Patented Sept. 11, 1906.

Application filed December 3, 1904. Serial No. 235,322.

To all whom it may concern:

Be it known that I, FREDERICK M. TURCK, a citizen of the United States of America, and a resident of the borough of Richmond, 5 city of New York, county of Richmond, State of New York, have invented certain new and useful Improvements in Rotary Printing-Presses, of which the following is a specification.

This invention relates to a rotary printing-press, and has for its object the provision of mechanism in a compact and simple arrangement whereby greatly-improved results may be attained in printing with a plurality 15 of colors on the same side of a sheet of paper, or on both sides, or on the same side of two or more sheets.

The invention consists, essentially, in a novel arrangement for leading the web or 20 webs through the press and submitting it to the action of the printing devices; also, in an adjustable mechanism for changing and redirecting the passage of the web; also, in various mechanical details and peculiarities 25 in the combination and arrangement of the various parts, substantially as will be herein-after described and claimed.

In the accompanying drawings, illustrating 30 my invention, Figure 1 is a side elevation of my improved rotary printing-press. Fig. 2 is a longitudinal section of the same on the line $x-x$ of Fig. 3. Fig. 3 is a top plan view of substantially one half of the machine, those rollers which extend entirely across the 35 frame being shown as broken off. Fig. 4 is a similar top plan view of the other half of the machine and shows the remaining portions of the broken-off rollers. Fig. 5 is a detail plan view in outline, showing the manner in 40 which the web of paper is passed around the impression-cylinder for the purpose of exposing both sides to receive an impression in order that each side may be printed in two colors. Fig. 6 is a similar outline view showing the manner in which a single web of paper 45 is passed about the impression-cylinder twice, so as to expose the same side of the paper twice in order that said side may receive an impression of four colors. Fig. 7 is a similar outline view showing the manner of 50 passing two webs of paper around a single impression-cylinder, each one exposing one of its sides to be printed, so that thus one side of each of two webs may receive an impression

in two colors. Fig. 8 is a detail side view of 55 the reversible boxes or bearings for the printing and impression cylinders, which boxes are removable and reversible for the purpose of enabling a substitution of printing and impression cylinders of different diameters. 60 Fig. 9 is a view of one of the threaded guide-rollers over which the paper is turned to a right angle.

Similar numerals of reference designate 65 corresponding parts throughout all the different figures of the drawings.

1 designates the main frame of my improved rotary printing-press, which may be of any suitable and desirable shape, &c., to accommodate therein the several mechanical 70 elements of the press.

2 denotes a single horizontal impression-cylinder which is suitably journaled in the frame 1. Vertically above the impression-cylinder 2 is one printing-cylinder 4, and horizontally opposite to the impression-cylinder 2 is another printing-cylinder 3. Thus I have a double printing-couple or a printing-triple, consisting of two printing-cylinders 75 coöoperating with a single impression-cylinder. 80

Although I do not desire to confine my press to any definite proportions of parts, yet one of the features which I wish to make prominent is that the forward portion of the main frame 1, or that portion which carries 85 the printing and impression cylinders and the inking attachments, is made, say, double the width of the ordinary press for a given area of printing-surface in order that the printing and impression cylinders may be twice as 90 long as usual, this being for the purpose of enabling each printing-cylinder to carry a double type-form and to permit two webs of paper to be passed around the impression-roller side by side or one web of paper passed 95 twice around the impression-roller, whereby two paper surfaces will be presented simultaneously to be printed by the two type-forms on the upper printing-cylinder and by the two forms on the lower printing-cylinder. 100

I wish to expressly say that I consider that my invention is broad enough to allow the printing devices on the printing-cylinders to be arranged in any desired manner, the aim being that each printing-cylinder should have 105 two sets of printing devices, if desired, one of which may print in one color and the other in another color, or they may all print in the

same color. For one of the printing-cylinders numbering wheels or cylinders or other devices may be substituted.

I will now briefly explain the inking contrivances for supplying ink to the printing-cylinders 3 and 4. At a suitable point relative to and below the printing-cylinder 3 the frame 1 carries an ink-fountain 9, having therein a fountain-roller 8. 5 indicates a composition roller serving as a ductor to transfer the ink from the fountain-roller 8 to the iron vibrating roller 7, which in turn applies ink to the composition form-roller 6, which applies it to the printing-cylinder 3. 10 Inasmuch as the printing-cylinder 3 has thereon two type-forms, the fountain 9 will be divided at the middle into two parts to permit, if desired, one half to contain an ink of one color and the other half an ink of another color in order that the printing-cylinder 3 may be enabled to print in two colors. Correspondingly the rollers 5, 6, 7, and 8 will serve with both colors, a part of each of said rollers serving with each color. Arranged in 15 connection with the printing-cylinder 4 is a pair of composition rollers 10 and 11, upon which lies the iron roller 13. 12 denotes an inking-cylinder, whose surface is in contact with the composition roller 11. Rollers 14 and 16 are composition rollers that apply ink to the inking-cylinder 12, and these rollers are arranged to vibrate. An iron roller 15 is in contact with the said rollers 14 and 16, and a ductor-roller 17 serves to transfer ink from 20 the fountain-roller 18 to the iron roller 15, said roller 18 being located within an ink-fountain 19, supported on the upper part of the frame 1. Ink-fountain 19 is divided into two parts, like ink-fountain 9, and the rollers 25 10, 11, 12, 13, 14, 15, 16, 17, and 18 will serve with both colors, a part of each serving with each color, and thus transferring the ink from the separate compartments of the fountain 19 to the separate type-forms on the printing-cylinder 4 in order that said cylinder may 30 be enabled to print in two colors, thereby having a like function with the printing-cylinder 3, though the colors may be different. In this manner the printing devices may 35 make four different-colored impressions or four different impressions of the same color—that is to say, four distinct imprints in one operation.

In Fig. 1 I show on the outside of the frame 1 an inclined rotative shaft 25, supported in bearings 26 and 27, which are bolted securely to the frame 1, said shaft having a crank 28, which is pivoted to the vibrating roller 7, a crank 29, pivoted to the vibrating roller 14, 40 and a crank 29^a, pivoted to the vibrating roller 16. Means for rotating or vibrating the shaft 25 may be supplied; but as they form no portion of the present invention and consist of common or well-known means a 45 detailed explanation thereof is unnecessary.

Further, it is unnecessary to explain in detail the rods 65 and 66, connecting with the handles 63 and 64, which are used in conjunction with the fountain-rollers 8 and 18 to control the ink-supply, and I have accordingly only delineated these in outline. 70

At the rear of the frame 1, on one half thereof, is a movable frame 20, supported on the horizontal shaft 33, which is journaled in the main frame 1 and acts as a pivot for the movable frame 20. Said frame 20 is capable of being lifted or lowered to a greater or less extent, and its movement is controlled by the handle 30 and a cam device actuated by said handle. In the movable frame 20 is journaled a roller 21, coöperating with a similar roller journaled in the frame 1. Also in frame 20 is journaled a feed-roller 22, coöperating with a similar feed-roller in frame 1, and a cylinder 23, coöperating with a similar cylinder in frame 1. By adjusting the movable frame 20 these cylinders and rollers may be placed nearer together or wider apart, these cylinders and rollers being shown here simply to indicate some of the 80 subsequent operations through which the web of paper may be passed, and said web of paper may obviously be a single sheet or two or more sheets, according to the work 85 which the press may be performing. 90

In the main frame 1 in the usual manner is supported the paper-roller 24, from which the web of paper-leads around the impression-cylinder 2 in the usual manner. An idler 67 is journaled in the main frame 1 and assists in directing the course of the web of paper so that it will reach the impression-cylinder with facility at all times. Referring to Fig. 8, it will be observed that the printing-cylinder 4 is supported in boxes 52, one at each 100 end. These boxes are each held in place by a screw 55. Each box has a round opening 59 for the journal of the printing-cylinder 4, said opening being out of the center or eccentric to the middle line of the box, so that 105 when the position of the box is reversed the opening 59 will take the position 60, where it will receive the journal of a substitute printing-cylinder of different diameter. 53 denotes a box employed at each end of the impression-cylinder 2 to support the same, said box having a round opening 57 therein eccentrically placed and adapted to take the position 58 when the boxes are reversed, so that 110 when the boxes are so reversed the openings 115 will receive the journals of another impression-cylinder of different diameter substituted in lieu of impression-cylinder 2. Furthermore, the lower printing-cylinder 3 is carried in boxes 54, which in the present example of the invention preferably bear 120 against the impression-cylinder bearings 53, while the boxes 54 are held in place by the screw-bolts 56. Boxes 54 have eccentric 125 round openings 61 to receive journals of the 130

printing-cylinder 3, which openings when the boxes are reversed assume the position indicated at 62, eccentric to the opening 61, and intended to receive the journals of a 5 substitute printing-cylinder of different diameter.

In Figs. 5, 6, and 7 I have illustrated certain different courses in which one or two webs may be led through the machine to receive a diversity of different or similarly colored impressions from the type-forms. This change in the passage of the web is made possible by the use of guide-rollers 45, 46, 46^a, and 47, which can be rearranged in the 15 several different ways illustrated and also in other ways. The most usual way in which these guide-rollers may be placed is shown in Figs. 2, 3, 4, and 5, in which the rollers 45 and 46 lie at right angle to each other, the 20 apex of the angle being centrally of the machine and behind the impression-roller 2, while the other ends of the rollers 45 and 46 will be near the sides of the frame 1. These 25 rollers 45 and 46 are suitably journaled in a sliding frame 70, having a proper amount of play to enable a proper register of the paper to be made in preparing the press for printing. The threading of the web for passage around the rollers 45 and 46 when they are in the 30 right-angled position (shown in Figs. 3 and 4) is indicated in the outline view of Fig. 5, where it will be seen that the web, which I have marked 50, coming from the roll 24 passes first over the idler 67, then around a 35 portion of the impression-cylinder 2 from underneath, over the cylinder 2, then backward horizontally, downward from above, and around the angular guide-roller 45, then making a right-angled turn on the way it 40 passes across horizontally to the guide-roller 46 and around the same from above, making in consequence a right-angled turn underneath which brings it into a position parallel to the direction which it took in being passed 45 to the first end of impression-roller 2, and it follows this direction to the other end of the impression-roller 2, passes underneath, around, and above the same, and then backwardly to the perforating-rollers 21 and the 50 cutting-cylinders 23. Thus it will be seen that the web 50 when it passes a second time around the impression-cylinder 2 presents a different side to the printing devices from that presented during its first passage 55 around the impression-roller, this change being due to the reversion of its course, owing to the winding about the two angularly-set guide-rollers 45 and 46. When the paper is thus wound on the impression-roller, it 60 must be obvious that the printing-cylinder 3 will print once on each side of the paper, while the printing-cylinder 4 will print once on each side, and hence in a single operation of the press there will be a printing of two col-

ors or the making of two impressions on 65 each side of the paper.

A different course of the paper is shown in Fig. 6. In this figure guide-roller 45 is shown in the same position as in Fig. 5; but guide-roller 46 is removed and guide-roller 46^a is supported in an inclined position parallel to the guide-roller 45, while a third guide-roller 47 is interposed between the rear ends of the two inclined rollers 45 and 46^a. We note that in the passage of the paper from the roll 24 it will be seen that the web, which I have marked 51, passes around one portion of the impression-roller 2 from underneath and then around the guide-roller 45 from above, making a turn underneath at right angles to the 70 course followed above until it reaches the guide-roller 46^a, passing from underneath, around, and above it, there making another turn at right angles, then running backwardly and around the roller 47 from above, 75 which will cause it to pass down and underneath said roller 47, when it is directed forwardly again underneath, around, and above another portion of the impression-roller 2 and then back rearwardly to the perforating-rollers 21 and the cutting-cylinders 23; but in this course of the web the wind is of 80 such a nature that when the paper passes the second time around the impression-roller 2 the same side is exposed to the action of the printing devices as when first passed around the roller 2, and consequently the printing-cylinders can print the same side of the paper twice, each time with two impressions, 85 whereby the same side of the paper may be 90 printed in four colors.

In Fig. 7 the rollers 45, 46^a, and 47 are arranged just the same as in Fig. 6; but I wind around them and the impression-cylinder two webs of paper instead of one coming 105 from two rolls, both of which can be suitably supported in the main frame in like manner as the roll 24 is carried. I have designated one of the webs 48. This passes around, underneath, and over the impression-roller 2, 110 then underneath, up, and over the guide-roller 45, making a turn at right angles, then over, down, and underneath the roller 46^a, making another turn at right angles, and then backwardly through the frame 20. The 115 other web, which I have marked 49, coming from the roll of paper in Fig. 2 passes underneath, around, and over the impression-roller 2 at the other end thereof and then backwardly above the web 48 into the frame 20. In this case two webs pass through the perforating-rollers, the feed-rollers, and the cutters. Hence in Fig. 7 only one surface of 120 each of two webs is presented to be printed, and upon each surface two impressions or 125 two colors can be printed at one operation.

In order to effectively use the angled guide-rollers, such as 45, 46, and 46^a, and cause the

web to make a turn at a right angle and in order to prevent the paper from running out of line on the roller and to prevent friction and liability to breakage of the web incident to the use of non-rolling angle-bars heretofore used, I construct these rollers in the peculiar manner illustrated in detail in Fig. 9, where it will be seen that the roller is provided with a screw-thread 71, running from end to end of the rollers. With such a screw-thread the paper as it travels forward is kept in position, and any tendency that it may have to become displaced on the guide-roller will be prevented, for the screw-thread will control its movement.

Obviously other ways of passing or directing one or more webs around the single impression-roller, in combination with suitable guide-rollers for controlling the direction of passage, may be devised without varying from the true intent and scope of my present invention, and I reserve the liberty of so doing.

The invention can be modified in many ways, if desired, from the forms just described—as, for instance, by omitting one of the printing-cylinders when it is desired to print in only one color on each side or only two colors on one side—or, if preferred, an extra impression-cylinder may be interposed between the present impression-cylinder and one of the printing-cylinders, the advantage of this being that the press in some cases can be more effectively made ready with this arrangement for printing.

The main shaft of the press is shown in Fig. 3 at 37. It carries a drive-pulley 31. On the drive-shaft 37 is a driving gear-wheel 36, which meshes with a gear-wheel 35 on the shaft of the printing-cylinder 4, which gear-wheel 35 in turn meshes with a gear-wheel on the shaft of impression-roller 2, (not shown,) that engages a gear 34 on the shaft of the printing-cylinder 3. The driving-gear 36 engages a gear-wheel 38 on the shaft of the inking-cylinder 12, which in turn meshes with and drives a gear-wheel 39 on the side of frame 1, and this drives a gear-wheel 40 on the end of the shaft 33, which shaft serves as a pivot for the frame 20. Gear 40 engages and drives a gear-wheel 41 on the side of the main frame, and this in turn engages a pinion 42 on the shaft of the upper perforating-roller 21. Pinion 42 engages and drives an intermediate 43, which transmits motion to a

gear-wheel 44 on the upper feed-roller 22. On the shaft of the upper cutting-roller 23 is a sprocket-wheel, and the sprocket-chain 32, which passes around said wheel, passes also around a sprocket-wheel on the end of the shaft of the printing-roller 4. In this manner a change of the size of the printing-couples will not require a change in the size of the cutting-cylinders, as there will always be one revolution of the cutting-cylinders to one revolution of the printing-couples.

The delivery or further disposition of the sheet when cut is accomplished in any usual manner, and as this is not a part of my invention it is unnecessary to describe it.

Having thus described my invention, what I claim as new, and desire to secure by Letters Patent, is—

1. The combination with a single impression-cylinder and two printing-cylinders, of means for inking different sections of the printing-cylinders so that different printing-forms thereon may serve to print different colors, and web-turning rollers situated at an angle to each other, said rollers being adapted to be changed from the angular position to one in which they are parallel to each other, and a third web-turning roller for use when the others are parallel, said web-turning rollers being provided with spiral screw-threads for properly alining the paper so that it will pursue its movement in a proper direction.

2. The combination of a single impression-cylinder, an upper printing-cylinder and a lower printing-cylinder, inking means for the printing-cylinders, said cylinders and inking means being constructed and operating so that different printing-forms may be inked with different colors, and means consisting essentially of angular web-turning rollers having spiral screw-threads thereon running from end to end for passing the web or webs of paper around the impression-cylinder, so that one or both sides of said web or webs may receive a plurality of colored impressions, substantially as and for the purpose described.

Signed at New York city this 29th day of November, 1904.

FREDERICK M. TURCK.
